CLAIM

The ornamental design for a jar, as shown and described.

DESCRIPTION

FIG. 1 is a top perspective view of a jar, in accordance with the present design.

FIG. 2 is a bottom perspective view of the jar of FIG. 1.

FIG. 3 is a top view of the jar of FIG. 1.

FIG. 4 is a bottom view of the jar of FIG. 1.

FIG. 5 is a front view of the jar of FIG. 1.

FIG. 6 is a rear view of the jar of FIG. 1.

FIG. 7 is a left side view of the jar of FIG. 1; and,

FIG. 8 is a right side view of the jar of FIG. 1.

The broken lines in the drawings showing the jar illustrate the portions of the jar that form no part of the claimed design.
